ELECTRIC FAN

Emil Mersmann, Post Oberbrugge, Germany

Application August 30, 1954, Serial No. 32,089

Term of patent 7 years

(Cl. D26—7)

FIG.1

FIG.2

FIG.3

FIG.4

FIG.5

Fig. 1 is a front elevation of the electric fan showing my new design,

Fig. 2 is a side elevation corresponding to Fig. 1,

Fig. 3 is an underneath view of the fan,

Fig. 4 is a perspective view of the fan, and

Fig. 5 is a plan thereof.

I claim:

The ornamental design for an electric fan, as shown.
